UNITED STATES PATENT OFFICE.

WALTER A. POST, OF NEWPORT NEWS, VIRGINIA.

CAR-COUPING.

SPECIFICATION forming part of Letters Patent No. 406,305, dated July 2, 1889.

Application filed January 29, 1889. Serial No. 297,906. (No model.)

To all whom it may concern:

Be it known that I, WALTER A. POST, a citizen of the United States, and a resident of Newport News, Warwick county, Virginia, 5 have invented certain Improvements in Car-Couplings, of which the following is a specification.

My invention consists of certain improvements in automatic car-couplings of the 10 character shown in Patent No. 393,660 granted to me November 27, 1888; and its object is to improve and simplify the means of attaching such a coupling to the cars, a further object being to so construct the devices that 15 the cars will be automatically uncoupled in the event of the derailment of one of the cars.

In the accompanying drawings, Figure 1 is an end view of a freight car, showing my improved coupling in position. Fig. 2 is a longitudinal section showing two cars coupled. Fig. 3 is a detached perspective view of the coupling; and Fig. 4 is a perspective view showing the construction of the pocket for attaching said coupling to the car.

25 A is the body of the car, B the common draw-head or coupler, and C the bumper-block. The two coupling-heads E and F are cast together, with an extension running back to the pivot-point, the casting being of 30 substantially the same form as that shown in my former patent, each casting having two heads, to one of which is pivoted a coupling-bar, and in the other is formed an opening or pocket to receive the end of a coupling-bar, 35 the front of the head being inclined so that the coupling-bar will ride up its face and drop into the pocket. This casting fits into a pocket P, secured to the frame of the car, and is pivoted therein by a flat-sided pin d, 40 running through a slot g on the casting, one end of a spring e being also carried in said slot g, with one of its ends resting against the flat side of the pivot-pin and the opposite end bearing against the end of the slot. As 45 this spring may be somewhat larger in diameter than the thickness of the casting, the pocket is cut away, as shown in Fig. 2, to permit the lateral movement of the spring.

In order to permit a free lateral movement 50 of the casting, I place flat springs b on the longitudinal stringers a, so that such springs

will bear upon the coupling-heads E and F in opposite directions, tending to center them, while permitting a great range of lateral movement.

55 As the casting does not extend far enough into the pocket P to be held in a perfectly horizontal position, I provide a strap m, passing underneath the casting at its outer end and fastened to the car by bolts n. The strip 60 does not fit closely to the sides of the casting, enough space being left to permit its lateral movement.

For ordinary use in uncoupling cars I use the same arrangement of levers and operating devices as that shown in my former patent, consisting of a bar J, pivoted to the center of the car and extending transversely across the same, with operating-handles j upon its opposite ends, rods k and l, extending from the bar to the operating-positions, and one being connected directly to the pivoted coupling-bar, and adapted to raise the same from its pocket in the opposite head, and the other being fulcrumed to a plate at 75 the bottom of the orifice in the coupling-head, the end of the coupling-bar resting upon this plate and being lifted out of the head when said plate is raised.

The lever K at the top of the car, connected 80 by a rod t to the transverse bar J, may also be employed to uncouple the cars from that position, if desired.

I have found that it is desirable, in the event of the derailment of one of the cars, to 85 detach the same from the remainder of the train; and to this end I have pivoted upon the top of each of the heads F a plate h, connected to a rocking lever o, pivoted at its center to the car, and having its opposite end 90 connected to the rod l.

The construction of the heads E, to which the coupling-bars are pivoted, is such that the bars are held in a perfectly horizontal position, and cannot fall below a certain 95 level; therefore, if a car be derailed, the coupling-bar on the next car, remaining perfectly level, will raise the plate n or head F as the car sinks, thus operating the lever o and depressing the lever l, and thus raising 100 the opposite coupling-bar out of its pocket through the medium of the lever J and rod k.

This pivoted plate *h* also serves to prevent the entrance of water to the pocket and the choking up of the pocket by ice or dust. This plate *h* is raised when coupling cars, the 5 coupling-bar raising it when moving up the face of the head *E*, rendering the coupling very easy.

In attaching my improved coupling to new cars the pocket *P* can be dispensed with, and 10 it is simply necessary to pivot the casting direct to the ordinary draw-head.

I claim as my invention—

1. The combination, in a car-coupling, of the opposite coupling-heads, an orifice in the 15 top of one of said heads to receive the coupling-bar carried by the other head, with a vertically-hinged top piece covering said orifice and adapted to be raised by the entrance or withdrawal of the coupling-bar from the 20 head, said top piece being connected to a system of levers operating the coupling-bars for the purpose of uncoupling the cars, substantially as specified.

2. The combination, in a car-coupling, of a casting carrying two coupling-heads, a laterally-extended pocket for receiving said casting and to which it is pivoted by a vertical pin to permit of the lateral movement of the casting in the pocket, substantially as specified. 25

3. The combination, in a car-coupling, of a casting carrying two coupling-heads, a laterally-extended pocket for receiving said casting, and to which it is pivoted by a vertical pin, and a spring interposed between 30 the casting and the rear of the pivot-pin, substantially as described.

In testimony whereof I have signed my name to this specification in the presence of two subscribing witnesses.

WALTER A. POST.
